UNITED STATES PATENT OFFICE.

WILLIAM L. PAUL, OF BERKELEY, CALIFORNIA, ASSIGNOR TO DEERE & COMPANY, OF MOLINE, ILLINOIS, A CORPORATION OF ILLINOIS.

ORCHARD PLOW.

Application filed June 9, 1922. Serial No. 567,161.

My invention relates to plows and more particularly to that type principally efficient and valuable in orchard cultivation, and has for its object the construction of such an implement in which controlling and plowing elements are so located that their operation will not result in damage to trees of an orchard while permitting a close cultivation.

Referring to the drawings in which similar numerals indicate indentical parts—

Figure 1 is a plan view of my improved plow. Figure 2 is a side elevation of Figure 1 showing the plow in operative position. Figure 3 is a side elevation of Figure 1 illustrating the plow raised. Figure 4 is an enlarged fragmentary view of the power lift mechanism and connected parts. Figure 5 is a detail perspective of the forward end of the plow. Figure 6 is a detail view of part of the rear furrowwheel support and Figure 7 is a detail of part of the draft device.

The main frame comprises a diagonally disposed composite beam formed, preferably, of flat beams or bars 1 and 2 spaced apart and parallel; the beam 2 is bent at 3 to extend forwardly parallel with the line of draft and with a landward frame beam or bar 4 which, at its rear end, is rigidly connected to the intermediate portion of the diagonal beam. The side members of the frame comprising the bars or beams 2 and 4 are bent arched, their forward ends being downwardly, and they are braced firmly apart by an inverted arch brace or spreader bar 5 bolted to both beams; braces 6 and 7 are interposed between the beams 2 and 4 and are bolted thereto. I thus provide a frame, the front portion of which is relatively wide to furnish laterally spaced bearing supports for the crank axle on which the land and furrow wheels are mounted, as hereinafter described, and the rear portion of which extends diagonally landward to form a support for the furrow openers.

The wheel system on which the plow is carried includes a landwheel 8, a front furrowwheel 9 and a rear furrowwheel 10. A crank axle 11 having forwardly directed cranks, extends transversely of the frame and is journaled in a bearing in a depending bracket 12 secured at an intermediate point on the beam 4, the bearing being sufficiently large to permit forward and rearward rocking movement of the axle and also a rocking movement transversely of the frame; I

secure the axle 11 from longitudinal movement by collars 13 and 14 on the axle on opposite sides respectively of the bracket 12.

The landward portion of the axle 11 is bent downwardly and terminates in a spindle 14 extending under the landward side of the frame toward the center thereof and on the outer portion of which is supported the land-wheel 8. The furrowward portion of the axle 11 is likewise bent downwardly and terminates in an outwardly extending spindle 16 on which is mounted a furrowwheel 9. Furrowwardly the axle is supported in a bearing on a forwardly extending arm 18 which is pivotally mounted, intermediate its length, between the lower end of a bracket 19, bolted to the beam 2, and the lower end of a radius arm 20 of a notched sector 21 which is rigidly attached to the bracket 19 and to a downwardly projecting extension 22 of a radius arm 23 of a notched sector 24 secured on the beam 2. A forwardly extending lever 25 is mounted on the pivot of the arm 18 and is adjustably attached to the forward end of said arm by a bolt 26 projecting into any one of a series of holes 27 which are provided in the arm for adjustment of the lever 25 to different positions on the arm 18 to increase or lessen its angular relation therewith. It is readily apparent that by operation of the lever 25 the axle 11 can be rocked transversely in its bearing on the beam 4, relatively to the frame to preserve the level of the plow. The lever 25 is provided with the usual type of latch to engage with the notches in the sector 21.

Rigidly bolted between the beams 1 and 2 are members 28 and 29 which form downward extensions of the frame, so that with said extensions and the downturned forward ends of the members 2 and 4 the frame as viewed in side elevation presents approximately the appearance of an inverted W, as best shown in Fig. 3. To each of the members 28, 29 is secured the standard of a plowing disk of any suitable type, and to the member 29 is also secured a bracket *a* composed of parts 30 and 31. The rear furrowwheel 10 is supported on an axle having a vertical spindle 32 journaled in a vertical bearing 33 and extending above the upper end thereof. A sleeve 34, preferably integral with the bearing 33, extends horizontally landward and journaled therein is an arm of a horizontally disposed U-shaped

member 35; the remaining arm of the member 35 is supported in bearings on the part 31 of the bracket *a*. A link 36 is connected to an eye in the upper end of the vertical bearing 33 and extends, in parallelism with the member 35, to connection with an eye in the part 31 of the bracket *a*. A rod *h* is attached to the member 35 by an eye in one end and extends forwardly at an upward 10 inclination to the member 35 to pass through an opening in the parts 30 and 31 of the bracket *a*. A coiled spring *i*, on the rod *h*, exerts its force against the member 30 and the bracket *a* and by expansion assists in 15 raising the rear of the plow, and when the plow is lowered the spring is contracted and so reduces the shock of the sudden dropping of the plow.

An upstanding arm 37 is rigidly attached 20 to the member 35 and has an eye in its upper end in which is hooked an end of a forwardly extending rod 38, said arm with the member 35 forming in effect a bell-crank lever. Secured to the landward crank arm 25 of the axle 11 is a casting 39 having a portion extending rearwardly to which is pivotally attached rearwardly extending link 40; the link 40 is bent upwardly at its rear end and through an eye 41 therein the threaded 30 end of the rod 38 extends and is rigidly and adjustably secured in place by nuts 42 and 43 on opposite sides respectively of the link 40, and by operation of the nuts 42 and 43 longitudinal adjustment of the rod 38 is accomplished to permit the rear furrow wheel to run in the same plane as the discs. The rod 38 and link 40 being rigidly connected together operate as a single thrust rod pivotally attached to the casting 39 and to the 40 arm 37, by which construction I avoid using a lost motion connection such as those heretofore used for a similar purpose employing slots, flexible connections, or telescoping parts, and provide for positively raising or 45 lowering the rear end of the frame through the swinging of the arched axle when it is actuated to raise the furrow openers out of operative position or to lower them into operative position, as hereinafter explained.

50 However, adjustment of the operating depth of the furrow openers does not affect the position of the rear furrow wheel. The curve in the link 40 is to avoid interference of the latter with the axle.

55 Mounted on the arch brace 5 is a forwardly extended bracket 44; a vertically disposed rocker arm 45 is supported, intermediate its length, on the bracket 44. The upper end of the rocker arm 45 is provided with an 60 eye in which is hooked an end of a steering rod 46; the steering rod 46 extends rearwardly to hook engagement with a steering arm 47 rigidly attached to the upper end of the spindle 32. On the forward termination 65 of the frame beam 4 is mounted, on a hori-

zontal pivot, a coupling 48, and a similar coupling 49 is mounted in a similar manner on the beam 2. A draft bar 50 is attached to the coupling 48 on a vertical pivot, and is provided with a series of holes 51 intermediate its ends; a draft bar 52 is secured to the coupling 49 in a similar manner and extends diagonally to the draft bar 50 which is composed of parallel flat bars *b* and *c* spaced apart and between which the draft bar 52 is 70 adjustably held by a bolt 53 passed through holes in the draft bar 50 and any one of a series of holes 54 in the draft bar 52.

75 Between the forward ends of the bars *b* and *c* are pivotally secured forwardly extending parallel links 55 and 56 adapted to be attached to a tractor; on the rear portion of the link 55 is rigidly mounted a furrowwardly extending arm 57, and in the furrowward end of the arm 57 is a hole in which 80 is hooked the forward end of a rod 58. The rod 58 extends rearwardly, substantially parallel with the draft bar 50, and its rear end is bent horizontally to an approximate right angle and is journaled in a casting 59 secured on a vertical pivot on the lower end of the rocker arm 45. Below the arch brace 5 and extending between the frame beams 2 and 4, and to which it is secured, is a shaft 60 on which is pivotally supported a forwardly extending arm 61. The arm 61 is formed of a single flat bar bent upon itself and embraces the rocker arm 45 below the pivotal support of the latter on the bracket 44. The rocker arm 45 is provided with a 90 pin 62 projecting from both sides of the rocker arm and engaging with slots 63 in the arm 61 and longitudinal thereof and operating as a stop to contact with either end of the slots 63 and limit the steering 95 movement of the wheel 10.

100 The plow is raised by traction power of the landwheel 15 by well known mechanism which in this instance includes a clutch mounted on the inner end portion of the 105 land wheel spindle so that it lies approximately midway between the side members of the frame. Consequently the land wheel may be set quite close to the frame, thereby 110 better adapting the plow for use in orchards where it is necessary to plow close to the trees and it is important to avoid damaging them. One of the parts 64 of the clutch is rigidly attached to the hub of the landwheel 115 8; the second part 65 of the clutch is loosely 120 mounted on the spindle 14 and has, preferably integral therewith, a sun gear 66. A planet gear 67 meshes with the sun gear 66 and is rigid with a stub shaft 68 journaled in a bearing on a member 69, the latter rotatably supported on the spindle 14 adjacent the sun gear 66. A link 70 has a bifurcated 125 end embracing the stub shaft 68 and is secured thereto by a pin 71 which passes through the stub shaft and the end of the 130

link 70; the upper end of the link 70 is pivotally attached to the rear end of an arm 72 which is pivoted intermediate its length on the beam 2 and on the same pivot is supported a lever 73 secured to the forward end of the arm 72 by a bolt 74 extending through the lever 73 and any one of a series of holes 75 in the forward end of said arm; by supplying a plurality of holes 75 it is possible to adjust the lever 73 to varying degrees of angularity relative to the arm 72 and the frame. By operation of the lever 73 the depth of plowing is regulated.

A tripping lever 76 is pivotally supported, intermediate its length, on the end of an arm 77 rigidly mounted on the axle 11. On the opposite side of the arm 77, and secured to the arm by the bolt which forms the pivot of the tripping lever 76, is a strap 78 parallel with said lever, and between the lower ends of the strap 78 and lever 76 is mounted a roller 79 which is adapted to rest upon a dog 80 to hold the clutch out of engagement. A relief spring 81 is attached to a lug 82 on the arm 77 adjacent the axle 11, and extends to the arch brace 5 to which it is connected. From the upper end of the tripping lever 76 a rope 83 leads to the tractor within convenient reach of the operator, whereby the tripping lever 76 can be operated to bring into play the mechanism just described to rock the axle 11 and raise the plow by the traction power of the land-wheel 8.

The front and rear of the plow are raised simultaneously, for when the clutch is tripped into operation and the axle 11 rocks and raises the plow, the rod 38, through its connection with the axle 11, is forced rearwardly, and as it is attached to the arm 37 on the U-shaped member 35 the latter is rocked raising the rear of the plow, the member 35 operating as a lever having its fulcrum in the sleeve 34. By this construction the parts just stated are well below the frame level and out of the way, and the wheel 10 and its mounting are within the transverse limit of the structure.

As previously stated the draft bars 50 and 52 are adjustably connected for the purpose of offsetting the plow from the line of travel of the tractor, the series of holes in each bar providing for such adjustment, and its retention by the bolt 53. The draft bar 50 and the rod 58 are substantially parallel, consequently when the plow is offset from the tractor, to operate the plow close to the trees, the links 55 and 56 are parallel with the line of advance of the tractor and plow, but if a turn or change in the direction of travel of the tractor is made the links 55 and 56 swing with the pull of the tractor rocking the arm 45, through connection of the rod 58 therewith and with the arm 57 on the link 55; rock-

ing the arm 45 actuates the steering rod 46, connected to the steering arm 47 on the spindle 32, consequently the rear furrowwheel 10 steers to follow the turn of the tractor. The steering rod 46 is made in two parts 70 and 75, one telescoping within the other, to provide for any needed adjustment in the length of the rod, and by means of a set screw *f* the two parts are held rigidly together.

When the plow is in operation, and from the moment the disks contact with the ground, the lowest point of the edge of the rear disk is in horizontal alinement with a similar point on the wheel 10, and this alinement is maintained irrespective of the depth of plowing. The depth of plowing is regulated by lowering the wheels 8 and 9, relatively to the frame, according to the depth desired, as is well understood by those familiar with the art. When the clutch is tripped the plow drops to contact with the ground, and if no previous plowing has been done there is an absence of furrows into which the furrowwheels 9 and 10 can travel, consequently all the wheels and the disks are on the same level, and as the landwheel 8 has not completed a revolution to again disengage the clutch the wheels are free to rise relative to the frame. As the plow advances the disks gradually seek their predetermined depth, which is reached by the time the clutch is disengaged, by which time the wheel 8 is rotating on the ground surface and the rear furrowwheel 10 has found the furrow. The front furrowwheel however also travels on the surface until a furrow has been formed in which it can travel.

The link 40 is pivotally connected to the casting 39 intermediate the length of the landward crank of the axle 11, and to one side thereof, and is rigidly attached to the forward end of the rod 38 which is pivotally connected to the arm 37 of the rear wheel mechanism, so that in the adjustment of the plow to a greater or less depth than that shown in Figure 2 of the drawings, the position of the rear furrowwheel is not affected, because the forward pivot of the link 40 by which it is connected to the casting 39 is in an approximately dead center relation to the axis about which the axle swings when the furrow openers are in operative position, and therefore vertical adjustment of the frame within the range required for depth adjustment does not move the link 40 endwise, since the point of connection of said link with the casting 39 then moves practically in a vertical line, and consequently it does not actuate the lever 37 to raise or lower the rear portion of the frame.

It will be noted that in the construction of my plow the parts have been so arranged as to present a low compact, efficient mechanism, and, as clearly shown in Figure 2, any

parts liable to cause injury to low hanging branches of an orchard, are either below the top level of the frame, or where any parts are above the level of the frame they are fended by the steering rod 46.

What I claim is—

1. In a wheeled plow, the combination with a frame and furrow openers connected therewith, of a land wheel, front and rear furrow wheels, means for raising and lowering the frame relatively to said wheels comprising an axle pivotally mounted on said frame and having a crank portion on which said land wheel is mounted, lifting means associated with the rear furrow wheel and adapted to be actuated to raise or lower the rear portion of the frame, and thrust mechanism connected with said lifting means and with the crank portion of said axle for actuating said lifting means when said axle is rocked.
2. In a wheeled plow, the combination with a frame and furrow openers connected therewith, of a land wheel, front and rear furrow wheels, means for raising and lowering the frame relatively to said wheels comprising an axle pivotally mounted on said frame and having a crank portion on which said land wheel is mounted, a bell-crank lever associated with the rear furrow wheel and adapted to be actuated to raise or lower the rear portion of the frame, and thrust mechanism connected with said lever and with the crank portion of said axle for actuating said lever when said axle is rocked.
3. In a wheeled plow, the combination with a frame and furrow openers connected therewith, of a land wheel, front and rear furrow wheels, and means for raising and lowering the frame relatively to said wheels comprising an axle pivotally mounted on said frame and having a crank portion on which said land wheel is mounted, means connecting the crank portion of said axle with said rear furrow wheel, and actuated by the swinging of said axle to raise or lower said frame with respect to said wheel, and power actuated means for swinging said axle to lift the frame.
4. In a wheeled plow, the combination with a frame and furrow openers connected therewith, of a front furrow wheel, a land wheel, means for raising and lowering the frame relatively to said wheels comprising an axle pivotally mounted on the frame and having crank portions on which said wheels are mounted respectively, vertically swinging means connected with the frame and carrying the rear furrow wheel, a lever connected with said rear furrow wheel supporting means and operable to raise and lower the rear portion of the frame relatively to said rear furrow wheel, a thrust rod connected with said lever and extending forward therefrom, a link pivotally connected

with the land wheel crank and connected with said thrust rod, for actuating said lever by the rocking of said land wheel crank, and power operated means for swinging said axle to lift the plow.

5. In a wheeled plow, the combination with a frame and furrow openers connected therewith, of a land wheel, front and rear furrow wheels, and means for raising and lowering the frame relatively to said wheels comprising an axle pivotally mounted on the frame and having a crank portion on which said land wheel is mounted, a lever associated with the rear furrow wheel, means actuated by said lever for raising or lowering the frame with respect to said rear furrow wheel, a thrust rod connected with said lever and extending forward therefrom, a member pivotally connected with the land wheel crank and adjustably connected with the forward end portion of said rod for actuating the same by the rocking of said land wheel crank, and power operated means for swinging said axle to lift said frame.

6. In a wheeled plow, the combination with a frame and furrow openers connected therewith, of a land wheel, front and rear furrow wheels, and means for raising and lowering the frame relatively to said wheels comprising an axle pivotally mounted on said frame and having a crank portion on which said land wheel is mounted, a curved link pivotally connected with the crank portion of said axle, a lever adapted to be actuated to raise or lower the frame with respect to said rear furrow wheel, a rod connecting said link with said lever, and power operated means for swinging said axle to lift said frame.

7. In a wheeled plow, the combination with a frame and furrow openers connected therewith, of a land wheel, front and rear furrow wheels, and means for raising and lowering the frame relatively to said wheels comprising an axle pivotally mounted on said frame and having a crank portion on which said land wheel is mounted, a lever adapted to be operated to raise or lower the frame with respect to said rear furrow wheel, a thrust member connected with said lever and with the crank portion of said axle between the axis thereof and the axis of the land wheel, and movable to approximately dead center relation to the axis of said axle when the furrow openers are in operative position, and means for rocking said axle to vary the depth of plowing.

8. In a wheeled plow, the combination with a frame and furrow openers connected therewith, of a land wheel, front and rear furrow wheels, and means for raising and lowering the frame relatively to said wheels comprising an axle pivotally mounted on said frame and having a crank portion on which said land wheel is mounted, a lever

- adapted to be operated to raise or lower the frame with respect to said rear furrow wheel, a thrust member connected with said lever, a curved link connected with said 5 thrust member and with the crank portion of said axle between the axis thereof and the axis of the land wheel, and movable to approximately dead center relation to the axis of said axle when the furrow openers 10 are in operative position, means for rocking said axle to vary the depth of plowing, and power actuated means for swinging said axle to lift the furrow openers out of operative position.
- 15 9. In a wheeled plow, the combination with a frame and furrow openers connected therewith, of a land wheel, front and rear furrow wheels, and means for raising and lowering the frame relatively to said wheels 20 comprising an axle pivotally mounted on said frame and having a crank portion on which said land wheel is mounted, parallel swinging members connected with the rear portion of said frame and having means for 25 supporting said rear furrow wheel, power operated means for rocking said axle to lift the furrow openers out of operative position, means connected with the axle below the level of the frame and with said swinging 30 members, and actuated by the rocking of said axle for swinging said parallel members to raise or lower the rear portion of the frame, and a spring interposed between said frame and said parallel members and operating 35 to assist in lifting the rear portion of the frame.
10. In a wheeled plow, the combination with a frame and furrow openers connected therewith, of a land wheel, front and rear 40 furrow wheels, and means for raising and lowering the frame relatively to said wheels comprising an axle pivotally mounted on said frame and having a crank portion on which said land wheel is mounted, parallel 45 swinging members connected with the rear portion of said frame and having means for supporting said rear furrow wheel, means for rocking said axle to lift the furrow openers out of operative position, means actuated 50 by the rocking of said axle for swinging said parallel members to raise or lower the rear portion of the frame, and a spring connected with the rear portion of one of said parallel members and with the frame for 55 aiding in lifting the rear portion of the frame.
11. In a wheeled plow, the combination with a frame having downturned front and rear end portions and intermediate side portions 60 spaced relatively widely apart transversely of the plow, the rear portion of said frame extending diagonally landward, of draft devices connected with the downturned front end portion of said frame, a furrow opener 65 connected with the downturned rear end portion thereof, a transversely disposed crank axle pivotally mounted in laterally separated bearings on said frame and having a spindle extending inward under one of the side portions thereof, land and furrow wheels 70 mounted on said axle, a rear furrow wheel supporting the rear portion of the frame, and devices mounted on said spindle between the side portions of the frame and adapted to be actuated by the rotation of 75 the land wheel to raise and lower the frame.
12. In a wheeled plow, the combination with a frame comprising a diagonally disposed beam having forwardly extending side members rigidly connected therewith, said 80 members being relatively widely spaced apart, a transversely disposed crank axle pivotally mounted on said frame and having a spindle extending inward under one of the side members thereof, a front furrow wheel, 85 a land wheel mounted on said axle, a rear furrow wheel on which the rear portion of said frame is supported for vertical adjustment, furrow openers carried by said beam, clutch mechanism mounted on said spindle 90 between the side members of the frame, means operable to actuate said clutch mechanism by the rotation of the land wheel, and devices actuated by said clutch mechanism for rocking said axle. 95
13. In a wheeled plow, the combination with a frame comprising a diagonally disposed beam having forwardly extending side members rigidly connected therewith, and provided with downturned front ends, 100 said members being relatively widely spaced apart, a transversely disposed crank axle pivotally mounted on said frame and having a spindle extending inward under one of the side members thereof, a front furrow wheel and a land wheel mounted on said 105 axle, a rear furrow wheel on which the rear portion of said frame is supported for vertical adjustment, furrow openers carried by said beam, a spreader brace interposed between the downturned front end portions of said beam members, and devices mounted on said axle between the side members of the 110 frame and adapted to be actuated by the rotation of the land wheel to rock said axle. 115
14. In a wheeled plow the combination with a frame and furrow openers connected therewith, of a front furrow wheel, a land wheel, a transversely disposed crank axle pivotally connected with the frame and supporting said land wheel, a rear furrow wheel, means connected with the frame for supporting the rear furrow wheel and operable to raise and lower the rear portion 120 of the frame with respect thereto, a lever for actuating said rear furrow wheel supporting means, a thrust rod connected with said lever, a link pivotally connected with the crank portion of said axle and connected with said rod, for actuating said lever 125 130

by the rocking of said axle, and power operated means for rocking said axle.

15. In a wheeled plow, a frame comprising laterally spaced side members, a transversely disposed crank axle pivotally mounted on said frame and having a spindle extending inward under one of the side member thereof, a front furrow wheel, a land wheel mounted on said axle, clutch mechanism mounted on said spindle between the side members of the frame, means operable to actuate said clutch mechanism by the rotation of the land wheel, and devices actuated by said clutch mechanism for rocking said axle to lift the frame.

16. In a wheeled plow, a frame comprising laterally spaced side members, a transversely disposed crank axle pivotally mounted on said frame and having a land wheel spindle extending inward under one of the side members and a furrow wheel spindle extending beyond the opposite side member of the frame, a furrow wheel mounted on the latter spindle, a land wheel mounted on the land wheel spindle, clutch mechanism mounted on the land wheel spindle between the side members of the frame, means operable to actuate said clutch mechanism by

the rotation of the land wheel, and devices actuated by said clutch mechanism for rocking said axle to lift the frame.

17. In a wheeled plow, a frame comprising laterally spaced bars one of which is arched, an axle journaled thereon and provided with a forwardly projecting crank positioned outside said arched bar and having an inwardly directed spindle at its end extending under said bar, a wheel journaled on said spindle, and means mounted on said spindle between the side members of the frame for swinging said crank to raise the frame.

18. In a wheeled plow, a frame comprising laterally spaced bars, one of which is arched, an axle journaled on said bars and having forwardly extending land and furrow wheel cranks at opposite sides of the frame, an inwardly extending spindle on the land wheel crank, a land wheel journaled on said spindle, an outwardly extending spindle on the other crank on which the furrow wheel is journaled, and lifting mechanism positioned between the side bars of the frame and connecting the inner end of the land wheel spindle therewith.

WILLIAM L. PAUL.

CERTIFICATE OF CORRECTION.

Patent No. 1,663,668.

Granted March 27, 1928, to

WILLIAM L. PAUL.

It is hereby certified that error appears in the printed specification of the above numbered patent requiring correction as follows: Page 1, line 32, strike out the word "bent" and insert the same before the word "downwardly" in line 33; page 2, line 59, for the word "locker" read "rocker"; page 3, line 83, strike out the word "lowering" and insert the words "vertically adjusting"; page 5, line 47, claim 10, before the word "means" insert the words "power operated" and line 49, after the word "means" insert the words "connected with the axle below the level of the frame and with said swinging members, and"; and that the said Letters Patent should be read with these corrections therein that the same may conform to the record of the case in the Patent Office.

Signed and sealed this 1st day of May, A. D. 1928.

(Seal)

M. J. Moore,
Acting Commissioner of Patents.
